FIG. 2

FIG. 3

FIG. 4

FIG. 5

FIG. 6

FIG. 7

FIG. 8

FIG. 9

FIG. 10

FIG. 1 is a top plan view of a medicine spoon or similar article showing my new design wherein the upper edge is flanged;

FIG. 2 is a side elevational view thereof;

FIG. 3 is an end view looking toward the left side of FIG. 2;

FIG. 4 is an end view looking toward the right side of FIG. 2;

FIG. 5 is a bottom plan view thereof;

FIG. 6 is a top plan view of the medicine spoon or similar article wherein the upper edge is devoid of a flange;

FIG. 7 is a side elevational view of FIG. 6;

FIG. 8 is an end view looking toward the left side of FIG. 7;

FIG. 9 is an end view looking toward the right side of FIG. 7; and

FIG. 10 is a bottom plan view of FIG. 6.

The essential features of my design reside in the full lines portions of the drawing, the conventional measuring scale in FIGS. 2 and 7 being shown in broken lines.

I claim:

The ornamental design for a medicine spoon or similar article, as shown and described.
